(57) **CLAIM**

The ornamental design for a swimming aid device fastener frame, as shown and described.

DESCRIPTION

FIG. 1 is a right side perspective view of the swimming aid device fastener frame showing my design in an environment of use;

FIG. 2 is a top perspective view thereof, shown in a folded configuration;

FIG. 3 is a rear elevation view thereof, shown in a folded configuration;

FIG. 4 is a front elevation view thereof, shown in a folded configuration;

FIG. 5 is a left side elevation view thereof, shown in a folded configuration;

FIG. 6 is right side elevation view thereof, shown in a folded configuration;

FIG. 7 is a top plan view thereof, shown in a folded configuration;

FIG. 8 is a bottom plan view thereof, shown in a folded configuration;

FIG. 9 is a top, front, right side perspective view thereof, shown in an unfolded configuration;

FIG. 10 is a front elevation view thereof, shown in an unfolded configuration;

FIG. 11 is a rear elevation view thereof, shown in an unfolded configuration;

FIG. 12 is a left side elevation view thereof, shown in an unfolded configuration;

FIG. 13 is a right side elevation view thereof, shown in an unfolded configuration;

(Continued)

FIG. 14 is a top plan view thereof, shown in an unfolded configuration; and,

FIG. 15 is a bottom plan view thereof, shown in an unfolded configuration.

The broken lines are shown for the purpose of illustrating portions of the swimming aid device fastener frame and form no part of the claimed design. The broken lines in FIG. 1 illustrating a person and swimming aid device are for the purpose of illustrating environmental matter and form no part of the claimed design.

1 Claim, 5 Drawing Sheets
